US0D1013662S

(12) **United States Design Patent** (10) **Patent No.:** **US D1,013,662 S**
(45) **Date of Patent:** **** Feb. 6, 2024**

(54) **WIRELESS EARPHONE**

(71) Applicant: **Shenzhen FuShiKe Electronic Co., Ltd**, Shenzhen (CN)

(72) Inventor: **Xiaohuang Yan**, Shenzhen (CN)

(73) Assignee: **Shenzhen FuShiKe Electronic Co., Ltd**, Shenzhen (CN)

(**) Term: **15 Years**

(21) Appl. No.: **29/803,504**

(22) Filed: **Aug. 13, 2021**

(51) LOC (14) Cl. **14-01**

(52) U.S. Cl.

USPC **D14/206**; D14/226

(57) **CLAIM**

The ornamental design for a wireless earphone, as shown and described.

DESCRIPTION

FIG. 1 is a front perspective view of a wireless earphone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of an encircled portion 9 of FIG. 1;

FIG. 10 is an enlarged view of an encircled portion 10 of FIG. 2; and,

FIG. 11 is an enlarged view of an encircled portion 11 of FIG. 3.

The broken lines in the drawings depict portions of the wireless earphone that form no part of the claimed design. The dash dot dash broken line designation 9 in FIG. 1 and the encircled portion of the wireless earphone in the enlarged view of FIG. 9, the dash dot dash broken line designation 10 in FIG. 2 and the encircled portion of the wireless earphone in the enlarged view of FIG. 10, and, the dash dot dash broken line designation 11 in FIG. 3 and the encircled portion of the wireless earphone in the enlarged view of FIG. 11, form no part of the claimed design.

1 Claim, 11 Drawing Sheets
